ROBERT C. PAULY, OF CINCINNATI, OHIO, ASSIGNOR TO THE AMERICAN LAUNDRY MACHINERY COMPANY, OF CINCINNATI, OHIO, A CORPORATION OF OHIO

DELINTING DEVICE FOR DRYING MACHINES

Application filed September 14, 1925. Serial No. 56,386.

This invention relates to improvements in delinting devices for drying machines used in connection with laundry, etc.

One object of the present invention is to provide such a device in which the delinting means is entirely enclosed within the casing and in which means is provided for removing the lint from the lint-collecting screen and depositing the lint in a container from which the lint may be removed from time to time as may be necessary.

More specifically, it is the object of the present invention to provide a traveling wiper or wipers which are adapted to engage the lint-collecting screen so as to deposit the lint into a container for removal.

Still more specifically, it is my object to provide such a wiper or wipers which are adapted to co-operate with other means so as to cause the lint to become packed in the container and at the same time to prevent the lint from being carried past the container and through the machine.

It is another object to provide a number of such wipers upon an endless traveling chain so as to have at least one of them always in wiping engagement with the screen, and also to provide means for adjusting the individual wipers so as to always effect proper wiping engagement with the screen.

A further object of this invention consists in providing means for automatically producing a signal to indicate when the lint collector or container has been filled and to provide also means for automatically stopping the operation of the fan of the drying machine as well as the movement of the wipers in case the signal just referred to should go unheated and the lint should be permitted to collect still further in the container.

Another object consists in providing means for preventing formation of pockets within which the lint might collect and in this way fail to be removed.

A still further object consists in providing means for preventing collection of lint upon the sprocket wheels of the chain which carries the wipers.

Other objects will appear from the follow-

ing description and claims when considered together with the accompanying drawings.

Fig. 1 is a front view of my improved device with parts broken away; Fig. 2 is a detail view showing one of the wipers and also one of the plates to prevent collection of the lint within a pocket or corner of the machine; Fig. 3 is a detail view showing the manner of mounting the wipers upon the sprocket chain; Fig. 4 is a detail view illustrating the wipers for preventing collection of lint upon the sprocket wheels; Fig. 5 is a vertical cross sectional view of the entire device showing the relative arrangement of the several parts; Fig. 6 shows the wiper felt in perspective with the slot for permitting adjustment; Fig. 7 is a detail view of a deflector plate arranged at the door of the casing so as to prevent escape of lint therefrom; Figs. 8 and 9 are detail views taken at 90° to each other and showing the operating mechanism for the sprocket chain which carries the wipers; Figs. 10 and 11 are detail views taken at 90° to each other and illustrating the means for automatically signalling the operator and stopping the operation of the entire device; and Fig. 12 is an electric diagram of the automatic signalling and stopping arrangement.

The drying machine here illustrated includes a casing 1 provided with the door 2 hinged across the front thereof so as to permit access to the machine interior. Arranged within a suitable chamber within the casing 1 is a tumbler in the form of a screened cylinder which is adapted to be rotated by an electric motor 3^a (shown in Fig. 12) in the well known manner and in which are contained the materials to be dried.

The casing is subdivided by suitable partitions, as indicated in Fig. 5, forming a heating chamber 5 within which the heating coils shown are located, a fan housing 6^b enclosing the rotary fan 6 which is arranged to deliver air into the heating chamber 5, an air inlet chamber 6^c and an exhaust chamber 8. The air inlet chamber 6^c communicates with the fan chamber through the usual endwise opening (not shown), and said fan chamber also communicates by way of a relatively small opening with the exhaust chamber 8. By this

construction, which will be recognized as old in the art, a recirculation circuit is established by operation of the fan, air passing from the fan housing 6b, through the heating chamber 5, up around the tumbler housing, downwardly through the opening 3a above the tumbler, through the tumbler, downwardly through the outlet opening 3b in the tumbler housing, downwardly through the screen 7 into the air inlet chamber 6c and thence again endwise into the fan housing 6b. A relatively small portion of the recirculated air will be continuously exhausted by way of the exhaust chamber 8 and approximately a corresponding amount of fresh air will be continuously drawn into the chamber 6c through the opening 6a, all as will be readily understood by one familiar with the art.

Extending across the entire width of the machine casing and located just inside of the front of the casing, there is provided an inclined deflector plate 10 having its lower edge portion bent to an angular form and suitably secured in such position. The upper edge portion of this deflector plate is provided with the felt strip 11 which engages the inner surface of the door 9 so as to thereby prevent escape of lint out past the door and at the same time to serve to deflect the lint into the zone of the screen 7 so as to be all caught thereby in the manner intended.

As a means of operating the fan and wipers, there is provided the electric motor 5a with the belt 13 which by means of suitable pulleys drives the shaft 14 extending across the front part of the machine casing at the bottom part thereof. The fan 6 is mounted upon the shaft 14 so as to be driven thereby, while the other end of this shaft extends out beyond the main part of the machine casing so as to drive other mechanism which is enclosed within an auxiliary casing and which includes shaft 17. This shaft 17 carries the worm 18 meshing with the gear 19. Mounted upon the shaft of the gear 19 there is provided the sprocket 20 which by means of the sprocket chain 21 drives the gear 22 and the sprocket 23 which is mounted upon the shaft 50 of the gear 22. Mounted within the casing and at the opposite or left hand side thereof there is provided the idler sprocket 24 which is companion to the sprocket 23 and about which there extends the sprocket chain 25 so as to be driven by the mechanism just now described. This sprocket chain 25 extends just above the screen 7 and carries the felt wipers 26 which are so constructed and arranged as to have effective wiping engagement across the entire upper side of the screen 7 during operation of the mechanism just referred to. Any desirable or suitable number of such wipers may be employed, but according to the present illustration there is provided just a sufficient number of such wipers to always

have one of them in engagement with the screen. The lint upon being removed by the wipers is deposited into the container 27 which is slidably mounted just beyond the end of the screen 7, as shown in Fig. 9. There is provided also across the top of the container 27 a member having an upwardly inclined lip portion 28 which is adapted to be engaged by the wipers 26 so as to ensure the lint being discharged or deposited into the container and not carried past the container, and scattered through the machine. The effect of such engagement between the wiper and the lip 28 is to also cause more or less packing of the lint within the container.

The sprocket wheels 24 are slidably mounted by means of the blocks and slots, illustrated in Fig. 2, so as to be slidably adjustable in the supporting brackets 29 which are suitably mounted on the inner wall of the casing. By means of set screws 30 which extend through the brackets 29 and engage the slideable blocks upon which the sprocket wheels are mounted, there can be effected any necessary adjustment of the sprocket wheels so as to maintain the proper degree of tautness in the sprocket chain.

Rockably mounted upon the auxiliary casing 15 is the bracket arm which carries the idler sprocket 25a to serve as a take-up for the slackness of the sprocket chain 21. Mounted also upon the cross bar 29a of the bracket 29 are the narrow felt strips 31 which are so arranged as to engage the opposite sides of the sprocket wheels 24 and in this way prevent accumulation of lint between the teeth thereof.

These wiper felts may be mounted in any suitable manner, for instance by means of angular strips 32 and the plates 33 upon the opposite sides thereof. The felts 26 are mounted upon the sprocket chain by means of inwardly extending bracket arms 34 which are secured to the links of the same, as illustrated in Fig. 3, and which are adapted to support at their inner ends the angular strips 35 between which the wiper felts are clamped by means of screw bolts 36. The felts are slotted, as illustrated at 37 so as to permit adjustment of the same to take up wear, this being readily accomplished by means of the screw bolts 36. The resilient metal sheets 38, which are secured upon the one side of the felts by means of the same screw bolts 36, will bend and thus during operation of the device will ensure uniform and effective engagement of the felts with the surface of the screen. The sheets 38 in this case are of sufficient resilience to maintain the felt wipers normal to the chain when they are idle.

The shaft 39 extends across and is mounted within the container 27 at a point near the bottom thereof and to one side so as to have rockable movement therein. This shaft has fixed thereupon the bottom plate or shelf 40

which is adapted to be swung downwardly when the load in the container reaches a certain predetermined point. The adjustable springs 41 are arranged between the downwardly extending projections 42 on the bearings of shaft 39 and the wall of the container so as to normally force the plate 40 upwardly to its horizontally extending position. Extending through the opening 43 in the wall 16 of the container is the arm 44 carried by the plate 40 and arranged so as to have its other end engaging under the arm 45 which is rockably mounted upon the inside of the frame of the machine structure. The shaft 15 46 of the arm 45 carries the two insulated spring arms 47 and 48, upon the other ends of which are provided the electric contacts 49 and 50 respectively. The inner or adjacent ones of the two corresponding pairs 20 of contacts 49^a and 50^a are connected by means of electric conductor 51.

The contacts 49^a are included in the circuit of the electric light 52 which is adapted to be operated as a signal when the weight of the 25 load in the lint container reaches a certain predetermined point. This is effected by depression of the plate 40 so as to effect closing of the circuit through the contacts 49^a by means of the mechanism just now described. 30 In case however such signals should not be heeded by the operator, who permits the device to continue operation and the lint to still collect in the container, then further lowering movement of the plate 40 will cause 35 the further rocking movement of the arm 45 so as to close the circuit across the contacts 50^a by means of the contact arm 50, automatically cutting out and stopping both of the motors as will be more thoroughly understood by reference to the electrical diagram in Fig. 12.

Referring to Fig. 12, it will be seen that upon momentary depression of the switch button 53, there will be completed a circuit 45 from the main line L' through the wire 54, switch 53, wire 55, switch 56, wire 57, switch 58, coil 59 and out through wire 60 to the other side of the main line L2. Upon energization of the coil 59, the circuit is closed 50 through contacts 61 and 62. Then the circuit through the motor 63 is completed from the main line L' through the wire 64, switch 62, wire 65, driving motor 3^a, wire 66 to the other side of main line L2. At the same time 55 a maintaining circuit is closed from one side of the main line L' through the wire 64, contact 62, contact 61, wire 67, switch 56, wire 57, switch 58, coil 59, and out through wire 60 to the other side of the main line L2. Thus 60 without holding the switch 53 closed any longer than momentarily, the circuit through driving motor 3^a is established and maintained closed so long as may be desired by the operator or until the motor circuit is automatically opened by means of the arrange- 65

ment above referred to. The circuit may of course be opened at any time by the operator by means of manual switch 56.

Likewise the fan motor 5a may be started by depressing momentarily the switch 69 so as to close the circuit from the main line L' through wire 70, closed switch 69, wire 71, closed switch 72, wire 73, closed switch 74, wire 75, coil 76, and out through the wire 77 to the other side of the main line L2. Energization of coil 76 will effect the closing of switches 78 and 79 with the result that the circuit through motor 5a is closed from the one side of the main line L' through the wire 80, closed switch 79, wire 81, motor 5a and through the wire 82 to the other side of the main line L2. Likewise the maintaining circuit is closed from the one side of the main line L', through wire 70, closed switch 69, wire 71, wire 83, closed switch 78, coil 76, and through wire 77 to the other side of the main line L2. The operation of motor 5a may also be interrupted at any time by manually opening switch 69.

During operation of the lint removing device in case the bottom plate 40 should be actuated by the weight of the lint, the circuit through contacts 49^a will then be completed and there will be established the circuit from the one side of the main line L', through wire 84, closed contacts 49^a, wire 85, and through the lamp 52 to the other side of the main line L2. Then in case this signal is not heeded by the operator who fails to empty the container, the accumulation of further weight of lint upon the plate 40 will cause actuation of the arm 48 so as to complete the circuit across the contacts 50^a. Then there is established the circuit from one side of the main line L' through wire 84, one of contacts 49, electric conductor 51, closed contacts 50^a, wire 86, coil 87, and out through the wire 88 to the other side of the main line L2. The energization of coil 87 causes switches 58 and 74 to both be operated automatically, with the result that the maintaining circuits through coils 59 and 76 are both broken, and consequently the circuits through both motors 3^a and 5^a are also broken, as will be readily understood. Thus the machine is automatically stopped in its operation to await removal and emptying of the lint container. With the empty container restored to position in the machine, the plate 40 will occupy horizontal position, as illustrated in Fig. 11.

Thus I have provided a lint collecting and discharging device which, except for the container, and driving mechanism is entirely enclosed within the machine casing and in which the lint is effectively and continuously removed from the screen during the operation of the machine. This lint is deposited in an efficient manner in a removable container and means are provided for automatically

signalling the operator when a certain amount of lint has been so deposited. Furthermore, the machine will automatically be stopped in case attention is not given to the emptying of the container at such time. Furthermore, I have provided an improved wiping device for removing the lint from the screen with means for adjusting the several parts and thereby increasing the efficiency. By keeping the screen clean, there is maintained an efficient circulation of air with the result that the drying of the materials is carried on most effectively, throughout the entire operation of the machine. This uniformity of treatment makes possible the obtaining of best results.

Likewise, I have provided means for preventing accumulation of lint within the corners or pockets of the machine casing and means also for preventing escape of lint outside of the casing. Thus besides providing an efficient and compact device, I have also guarded against the danger of such lint which might otherwise escape from the casing, being sucked in through the screen opening and passed into the heating chamber without the detrimental result which is produced in some of the present forms of such devices.

What I claim is:

1. In a structure of the character described, the combination of a chamber having an outlet through which lint laden air is adapted to be passed, a lint storage reservoir having a mouth at its upper end, means arranged in the vicinity of said chamber outlet for collecting lint from the air passing therethrough, means for transferring lint from said collecting means to a point above the mouth of said storage reservoir, whereby said lint will fall by gravity into said reservoir, and means above said reservoir mouth and adapted for cooperative engagement with said transfer means for insuring the removal of lint therefrom.

2. In a structure of the character described, the combination of a chamber having an outlet through which lint laden air is adapted to be passed, a lint storage reservoir, means arranged in the vicinity of said chamber outlet for collecting lint from the air passing therethrough, means for delivering lint from said collecting means to said reservoir, means for indicating when a predetermined quantity of lint has been stored in said reservoir, and means for automatically operating said indicating means.

3. In a structure of the character described, the combination of a chamber having an outlet, means for producing a flow of lint laden air through said outlet, a lint storage reservoir, means arranged in the vicinity of said outlet for collecting lint from the air passing therethrough, means for delivering lint from said collecting means to said reservoir, and means for automatically stopping the operation of said air flow producing means when

a predetermined quantity of lint has been stored in said reservoir.

4. In a structure of the character described, the combination of a chamber having an outlet, means for producing a flow of lint laden air through said outlet, a lint storage reservoir, means arranged in the vicinity of said outlet for collecting lint from the air passing therethrough, means for delivering lint from said collecting means to said reservoir, and means for automatically producing a signal when a predetermined quantity of lint has been stored in said reservoir and thereafter stopping operation of said air flow producing means when a further predetermined quantity of lint has been stored in said reservoir.

5. In a structure of the character described, a chamber provided with an outlet through which lint laden air is adapted to be passed, a rotatable member in said chamber, a lint storage reservoir, means arranged in the vicinity of said chamber outlet for collecting lint from the air passing therethrough, means for delivering lint from said collecting means to said reservoir, and means for automatically stopping the rotation of the rotatable member when a predetermined quantity of lint has been stored in said reservoir.

6. In a structure of the character described, a chamber provided with an outlet through which lint laden air is adapted to be passed, a rotatable member in said chamber, a lint storage reservoir, means arranged in the vicinity of said chamber outlet for collecting lint from the air passing therethrough, means for delivering lint from said collecting means to said reservoir, and means for automatically producing a signal when a predetermined quantity of lint has been stored in said reservoir and thereafter stopping the rotation of said rotatable member when a further predetermined quantity of lint has been stored in said reservoir.

7. In a structure of the character described, a chamber provided with an outlet, a work receiving member arranged in said chamber, means for rotating said work receiving member, means adapted when actuated for producing flow of lint laden air through said outlet, means for actuating said air flow producing means, a lint storage reservoir, means arranged in the vicinity of said chamber outlet for collecting lint from the air passing therethrough, means for delivering lint from said collecting means to said reservoir, and means for automatically producing a signal when a predetermined quantity of lint has been stored in said reservoir, and thereafter stopping the operation of said means for rotating the work receiving member and the means for actuating said air flow producing means when a further predetermined quantity of lint has been stored in said reservoir.

8. In a structure of the character described, the combination of a chamber having an out-

let through which lint laden air is adapted to be passed, a lint storage reservoir having a mouth at its upper end, means arranged in the vicinity of said chamber outlet for collecting lint from the air passing therethrough, means for transferring lint from said collecting means to a point above the mouth of said storage reservoir, whereby said transferred lint will fall by gravity into said reservoir, and a cleaning and packing member inclined upwardly and forwardly toward the lint collecting means so that it overhangs the mouth of said reservoir, said cleaning and packing member being adapted for co-operative engagement with the lint transferring means when said means is above the mouth of said reservoir.

9. In a structure of the character described, lint transfer means, operating means therefor including a rotatable sprocket wheel and a chain traveling thereover and both normally exposed to lint, and means co-operating with said sprocket wheel for removing lint therefrom.

25 10. In a structure of the character described, the combination of a lint transfer member, operating means therefor including a chain upon which said lint transfer member is mounted and a sprocket wheel over which 30 said chain travels, and felt strips engaging opposite sides of said sprocket wheel for preventing the accumulation of lint thereon.

11. In a structure of the character described, a chamber having an outlet, a rotatable work-receiving member in said chamber, means for producing a flow of lint laden air through said outlet, a lint storage reservoir, means arranged in the vicinity of said outlet for collecting lint from the air passing therethrough, means for delivering lint from said collecting means to said reservoir, and means for automatically stopping the operation of said air flow producing means and for automatically stopping the rotation 45 of the work-receiving member when a predetermined quantity of lint has been stored in said reservoir.

In testimony whereof I hereby affix my signature.

50 ROBERT C. PAULY.
